UNITED STATES PATENT OFFICE.

JOHN KESSLER, OF MARSHALLTON, DELAWARE.

RAIL-JOINT.

1,151,275.

Specification of Letters Patent. Patented Aug. 24, 1915.

Application filed November 24, 1914. Serial No. 873,788.

To all whom it may concern:

Be it known that I, JOHN KESSLER, a citizen of the United States, residing at Marshallton, in the county of New Castle and State of Delaware, have invented new and useful Improvements in Rail-Joints, of which the following is a specification.

The present invention relates to improvements in means for connecting the ends of railway rails and the object of the invention is to produce a device of this class which is comparatively simple and which shall be thoroughly effective in securing the rails against lateral or vertical movement, preventing the tilting of the rails as well as the creeping of the same, but affording the said rails the limited longitudinal movement necessary for expansion and contraction.

With the above and other objects in view, the improvement resides in the construction, combination and arrangement of parts set forth in the following specification and falling within the scope of the appended claims.

In the drawings: Figure 1 is a perspective view of two rails connected in accordance with the present invention, Fig. 2 is a transverse sectional view approximately on the line 2—2 of Fig. 1, Fig. 3 is a perspective view of the base plate, Fig. 4 is a sectional view approximately on the line 4—4 of Fig. 3 but illustrating a filler plate inserted between the members comprising the base plate to widen the same to permit of the accommodation of a rail having a widened base, Fig. 5 is a sectional view approximately on the line 5—5 of Fig. 3 showing the strut flanges arranged within the sleeve, Fig. 6 is a perspective view of a portion of a base plate in which the strut flanges are dispensed with, Fig. 7 is a similar view of a still further modified form of base plate in which the same is provided with a central channel and a filler or brace member arranged within the channel, Fig. 8 is a transverse sectional view approximately on the line 8—8 of Fig. 1, Fig. 9 is a perspective view of one of the fish plates, Fig. 10 is a similar view of one of the splice bars, Fig. 11 is an elevation of the bolt with the jam and locking nuts thereon, Fig. 12 is a face view of the jam nut, Fig. 13 is an elevation of the locking nut, and Fig. 14 is a sectional view illustrating the manner of securing the lock nut upon the jam nut.

Referring now to the drawings in detail, R—R indicate the meeting ends of two rails

of the ordinary construction, and T the ties upon which the rails rest.

My improved joint contemplates the employment of a rail chair which includes a base plate 1 upon which the rails rest and which in turn rests upon at least two of the ties T. The base plate in the preferred form of the device includes two similar members each being formed upon its outer edge and at a suitable distance from its opposite ends with a longitudinally extending vertically projecting guard rib 2 said plates being formed upon their inner longitudinal edges, at a suitable distance from their opposite ends with depending longitudinally extending flange members 4, the same providing truss plates or reinforcements for the central portion of the base 1. The plate 1 is illustrated in detail in Fig. 3 of the drawings and it will be noted that the members beyond the ends of the guard ribs 2 and likewise beyond the truss flanges 4, are provided with spike openings 5, and the plates are connected by suitable securing means 6, such as nuts and bolts, which pass through transverse openings in the flanges 4. The plate is of a width to accommodate ordinary rails, but if it is required that the plates receive rails having extraordinary wide base portions, a filler plate or block 7 may be inserted between the meeting ends of the plates and secured thereto by the elements 6, such construction being illustrated in Fig. 4 of the drawings. Further, to reinforce the structure a sleeve 8 may be provided which snugly receives the flanges 4, and, as above stated, filler members may be arranged between the flanges to force the outer faces of the same against the inner faces of the substantially U-shaped sleeve 8, the securing elements 6 retaining the sleeve upon the flanges (see Fig. 5).

In Fig. 6 of the drawings there is illustrated an integral base or rail plate 9 which is substantially similar to that previously described, the same including side guard ribs 10 which are spaced from the ends of said plate and the portions of the plate beyond the ends of said guard ribs 10 are provided with spike openings 11. The plate 9 is not provided with the brace or truss flanges 4 and is designed for use upon a rail joint which is not subjected to heavy traffic.

In Fig. 7 I have illustrated a still further form of base or rail plates, the same being indicated by the numeral 11 and includes

side ribs 12 similar to the ribs 10 and 2. The plate 11 is bulged downwardly centrally and longitudinally to provide a substantially V-shaped truss 13 as well as a pocket 14 for the reception of a V-shaped filler block or reinforcing plate 15.

The guard ribs do not contact with the longitudinal edges of the bases of the rails, and the webs of the rails are provided with 10 the usual elongated bolt openings. Duplicate joint bars 17 are applied upon the opposite sides of the abutting rail ends and fit the fishing spaces of the fish plates or filler members associated therewith in a 15 manner to be more particularly explained. The joint bars are of the angle bar type, each consisting of an upright splice member 18 having its upper edge provided with an angular bearing head 19 and its lower edge 20 formed with the inclined outwardly extending foot flange 20, the extremity of which being provided with a depending longitudinally extending rib 21 which is adapted to abut with the inner face of the ribs 2 of 25 any of the base plates 1 previously described. The filler or fish plates of the joint members 17 each comprise a curved reduced flexible body portion or web 22 having its upper edge provided with an outturned head 23, the opposite walls or faces of which being angular, the upper face engaging the underface of the head of the rail and the lower face being engaged by the angular head 19 of the member 18. The opposite 30 edge of the member 22 is outturned providing a flat face 24 which is contacted by the lower straight face of the member 18. The fish or filler plates 22 and the vertical member 18 of the angle bar of the joint bars 17 35 are provided with a plurality of spaced openings which register with the openings in the webs of the rails, bolts 25 passing through the said openings. These bolts have their ends engaging with jam nuts 26, and the said bolts are provided with reduced extensions 27 having their threads at 40 a different pitch from the threads engaged by the bolts 26, the said extensions 27 being engaged by lock nuts 28. The jam nuts 26 45 preferably have their outer faces provided with a plurality of scallops 29 and the locking nuts 28 are provided with malleable flanges 30 upon their inner faces, so that 50 after the jam nuts have been screwed entirely home upon the main threads of the bolts 25 and the lock nuts screwed entirely home or into tight frictional contact with the outer faces of the jam nuts, a violent blow of a hammer upon the flange 30 will 55 cause the said flange to be bent into one of the scallops 29, and thus effectively lock the nuts upon the bolts.

In Fig. 14 the jam nut 31 may have its outer face smooth, and the flange 32 of the 60 locking nut 33 extended so a portion of the

same may be bent over one of the sides or faces of the nut 31, as indicated by the numeral 34.

The opposite outer corners of the foot portions 20 of the angle bars 18 are cut away or scalloped, as at 35, the said cut away portions being arranged adjacent to the spike openings in the base plates, so that when spikes 36 are passed through the openings into the ties T, the heads 37 of the 75 same will contact with the upper faces of the base flanges of the rails as well as with the walls provided by the said scallops or cut away portions 35.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:

1. In a rail joint, the combination with two abutting rails, ties for the rails, a base plate upon the ties and providing rests for the rails at the ends of the rails, said plate including guard ribs which terminate a distance from the ends of the plate, duplicate joint bars arranged upon the opposite sides 90 of the abutting rail ends, each of the said bars comprising an angle member, the upper member of each having an angular inwardly extending head, its lower portion provided with an outwardly extending rail engaging 100 foot, said foot being formed with a down-turned flange which contacts with the guard flange of the base plate, the corners of the foot being notched fish plates, each having a reduced web portion and an outwardly 105 extending head which rests upon the head of the angle bar and beneath the heads of the rails, and the lower portion of each of said fish plates having an outturned member which contacts with the flat inner face of 110 the joint bars, securing spikes passing through the base plates and having their heads resting upon the base flanges of the rails and contacting with the walls provided by the notched corners of the joint 115 bars, and transverse means for connecting the joint.

2. In a rail joint, the combination with two abutting rails, ties for the rails, a base plate upon the ties and providing rests for 120 the rail ends, said plate including guard ribs which terminate a distance from the ends of the plate, the said plate being centrally formed upon its underface with a longitudinally extending truss, duplicate 125 joint bars arranged upon the opposite sides of the abutting rail ends, each of said bars comprising an angle member, the upper member of each of the said bars having an angular inwardly extending head and its 130

- lower portion provided with an outwardly extending rail engaging foot, said foot being formed with a downturned flange which contacts with the guard flange of the base 45
- 5 plate, the corners of the foot being notched, fish plates each having a reduced web portion and an outwardly extending head which rests upon the head of the respective joint bars and beneath the heads of the rails, and
- 10 the lower portion of each of the said fish plates having an outturned member which contacts with the flat inner face of the joint bars, securing spikes passing through the base plates and having their heads resting
- 15 upon the base flanges of the rails and contacting with the walls provided by the notched corners of the joint bars, and transverse means for connecting the joint.
3. In a rail joint, the combination with 20 two abutting rails, ties for the rails, a base plate upon the ties and providing rests for the rails at the meeting ends of the rails, said plate including guard ribs which terminate a distance from the ends of the plate,
- 25 said plate comprising two members each being formed with a depending truss flange, means for connecting the flanges, duplicate joint bars arranged upon the opposite sides of the abutting rail ends, said bars each
- 30 comprising an angle member, the upper portion of each member having an angular inwardly extending head, the lower portion and each of said bars provided with an outwardly ex- 65
- 35 tending rail engaging foot, said foot being formed with a downturned flange which contacts with the guard flange of the base plate, the corners of the foot being notched, fish plates each having a reduced web portion and an outwardly extending head which rests upon the head of the joint bars and beneath the heads of the rails, and the lower portion of each of the said fish plates
- 40 having an outturned member which contacts with the flat inner face of the joint bars, securing spikes passing through the base plates and having their heads resting upon the base flanges of the rails and contacting with the walls provided by the notched corners of the joint bars, and transverse means 70
- 45 for connecting the joint.
- In testimony whereof I affix my signature in presence of two witnesses.
- JOHN KESSLER.
